(57) **CLAIM**

The ornamental design for a rail connector for an electrical switch, as shown and described.

DESCRIPTION

FIG. 1 is a perspective view of a rail connector for an electrical switch according to our new design.

FIG. 2 is a front elevational view thereof, the rear view being a mirror image.

FIG. 3 is a left side elevational view thereof, the right side view being a mirror image.

FIG. 4 is a top plan view thereof; and,

FIG. 5 is a bottom plan view thereof.

1 Claim, 4 Drawing Sheets

FIG. 1

FIG. 2

FIG. 3

FIG. 4

FIG. 5
